UNITED STATES PATENT OFFICE.

CHARLES CLAYTON JOHNSON, OF NEWBURGH, NEW YORK.

WATER-LEVEL ALARM FOR DRIP-PANS.

1,283,200.

Specification of Letters Patent.

Patented Oct. 29, 1918.

Application filed July 20, 1917. Serial No. 181,749.

To all whom it may concern:

Be it known that I, CHARLES CLAYTON JOHNSON, a citizen of the United States, and a resident of Newburgh, in the county of Orange and State of New York, have invented a new and Improved Water-Level Alarm for Drip-Pans, of which the following is a full, clear, and exact description.

My invention relates to an electric alarm for water levels and more particularly relates to an alarm to be employed in connection with the drip pan of a refrigerator or in connection with an analogous water receptacle.

Objects of the invention are to provide an alarm of the indicated character which will not interfere with the convenient placing and removal of the pan, and to provide a novel means for adjusting a float-controlled alarm for varying the water level at which the alarm will be sounded.

An important object of the invention also is to provide an attachment of the class described that may be readily applied to a drip pan and readily connected up with the electric alarm circuit or disconnected in the placing and removal of the pan.

Other objects of the invention and its advantages will appear as the description proceeds.

Reference is to be had to the accompanying drawings forming a part of this specification in which similar reference characters indicate corresponding parts in all the views, it being understood that the drawings are merely illustrative of one example of the invention.

Figure 1 is a transverse vertical section through an alarm embodying my invention, showing the same applied to a refrigerator partly shown in longitudinal vertical section;

Fig. 2 is a fragmentary plan view of the same, the refrigerator being omitted and the alarm circuit being shown diagrammatically;

Fig. 3 is a vertical section on the line 3—3, Fig. 2.

In the illustrated example of my invention I have shown the same associated with a drip pan A and the lower portion B of a refrigerator. On the refrigerator below the bottom thereof an electric circuit is arranged, including conductor wires 10, a bell

or equivalent audible signal 11, and a battery 12 supported in brackets 13.

I provide a clamp 14, the rear member 15 of which carries a clamp screw 16 to bind against the outside of the pan A while the main body or face plate of the clamp 14 lies at the interior of the pan, the screw thus acting to clamp the side of the pan between the said screw and the face plate of the clamp. A hinge leaf 17 is riveted or otherwise secured to the clamp 14. The leaves 17, 18 of the hinge are connected by a knuckle hinge 19, hereinafter more particularly referred to, and said leaf 18 is secured by screws 18' or equivalent fasteners to a block 20 constituting a support for a float arm 21 pivoted as at 22 between ears 23 on the block 20, so that the ball float 21^a thereof will be subject to the water in the pan A.

The float controls an electric switch for which purpose a head 24 is secured to or formed on the float arm 21 at the opposite side of the pivot from the float 21^a and is adapted upon the rising of the float to be pressed against separated contacts 25 which are formed by the heads of transverse bolts 80 extending through the block 20, said bolts serving to secure sockets 26 to the opposite face of the block from the said contact heads of the bolts. The sockets 26 have vertical flaring slots 27 that detachably receive contact pins or bolts 28 which are carried by a block 29 and extend transversely therethrough and are provided with binding posts 30 for the terminals of the circuit wires 10.

By the described arrangement a slip connection is established between the contact pins or bolts 28 and the sockets 26 and when the said pins and sockets are engaged, the heads of the pins 28 contact with the ends 95 of the contact bolts 25 carried by the block 20. Therefore, the rising of the float 21 will move the head 24 thereof into engagement with the heads of the contact bolts 25 thereby closing the circuit; for sounding the 100 alarm and upon the float dropping to a lowered position, the circuit will be broken. It will be clear, therefore, that the pan A may be removed from beneath the refrigerator for the dumping of the water and with 105 it the block 20 and the float arm by disengaging the sockets 26 from the contact bolts 28, the said sockets and contact bolts having

a slip connection by reason of the slots 27. When the pan is replaced beneath the refrigerator, the sockets 26 are again engaged with the bolts 28 to establish metallic connection with the contacts 25.

In order to adjust the angular relation of the hinge leaves 17, 18 for varying the water level at which the float 21 will close the circuit through the contacts 25, the hinge pin 10 31 of the knuckle hinge 19 is provided with threads receiving a wing nut 32, or the like, so that the tightening up of the nut will bind the knuckle and maintain the block 20 in a given angular relation to the clamp 14 15 whereby to vary the angle through which the float arm will be moved by the rising water before engaging the contacts 25.

I wish to state in conclusion that although the illustrated example constitutes a practical embodiment of my invention, I do not limit myself strictly to the mechanical details herein illustrated, since manifestly the same can be considerably varied without departure from the spirit of the invention as 25 defined in the appended claims.

Having thus described my invention I claim as new, and desire to secure by Letters Patent:

1. In a circuit closer of the class described, 30 a structure attachable to a water receptacle, and adapted to be associated with a relatively fixed support, an element carrying terminals for electric conductors, a switch comprising contact members associated respec-

tively with the said structure and with the 35 said element, a float controlled arm pivoted on said structure and adapted to control said switch, and means forming a separable connection between the said structure and said element to permit removal of the water receptacle with the attached structure and float. 40

2. In a circuit closer of the class described, separable switch elements, means establishing a slip connection between said 45 elements, coacting contact members carried by the respective switch elements, means to attach the other of said elements to a water receptacle, and a float controlled arm pivotally mounted on the latter element and 50 adapted to engage the contact members thereof.

3. In a circuit closer of the class described, a float controlled arm, a structure on which the said arm is pivoted, means to support 55 said structure, contact members on said structure to which members the said arm is pivoted, contact members on said structure with which the said arm is adapted to engage, sockets on said structure, an element 60 having contact members detachably receivable in the said sockets to engage the first mentioned contact members, and means on said element adapted for connection with the conductor wires of an alarm circuit, said 65 means being connected with the contact members of said elements.

CHARLES CLAYTON JOHNSON.
